UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A BABY'S CREEPING-APRON.

SPECIFICATION forming part of Design No. 14,456, dated November 27, 1883.

Application filed September 26, 1883. Term of patent 3½ years.

To all whom it may concern:

Be it known that I, MARY TURNER, of the city, county, and State of New York, have invented and produced a new and original 5 Design for a Pattern of a Baby's Creeping-Apron, (numbered 8,913;) and I do hereby declare that the engraved prints accompanying this specification convey to any one accustomed to using paper patterns a clear understanding of how a garment made up by the pattern will appear.

The design shows an ample front portion and a corresponding back portion, and exhib-

its drawing-cords at the neck and lower edges for the purpose of adjustment. Coat-sleeves 15 are added.

What I claim as my invention, and desire to secure by Letters Patent, is—

The design for a baby's creeping-apron, as shown in the engraved prints accompanying 20 this specification.

MARY TURNER.
